(57) **CLAIM**

The ornamental design for a lock, key and catch set, as shown and described.

DESCRIPTION

FIG. 1 is a perspective view of a lock, key and catch set according to our new design;
FIG. 2 is a front view thereof;
FIG. 3 is a rear view thereof;
FIG. 4 is a bottom view thereof;
FIG. 5 is a top view thereof;
FIG. 6 is a side view thereof; and,
FIG. 7 is an opposite side view thereof.
Any elements shown in broken lines form no part of the claimed design.
